METHOD AND APPARATUS FOR MANUFACTURING SEAMLESS PIPES AND TUBES

Bryant Bannister, Mount Lebanon, Pa.

Application June 21, 1934, Serial No. 731,772

15 Claims. (Cl. 80—13)

This invention relates to an improved method and apparatus for manufacturing seamless pipes and tubes, and more particularly to that operation which is known as "piercing", although not limited thereto.

In seamless pipe and tube practice, the designing of the metal-working pass has largely been by "rule of thumb". That is to say, numerous passes have been found, from experience, to be satisfactory to at least some degree, and have accordingly been repeatedly imitated. Certain types of metal working rolls are known to perform in a substantially predetermined manner, and the component elements of the pass, such as mandrel 5 and guiding members, are modified within narrow limits in attempting to acquire a superior work-piece from the mill. It may, therefore, be safely said that, of all rolling operations, seamless tube practice has, in particular, been largely an art. 10

20 This is for the reason that the metal in the pass of a seamless pipe or tube mill is moved in a manner which is decidedly complex.

From a consideration of all types of seamless tube operations, it clearly appears that the first 25 objective was to obtain a work-piece having certain characteristics. The second objective was to alleviate, as much as possible, all conditions not conducive to the free forward movement of the metal of the work-piece.

30 A severe and injurious upsetting action occurred, and resulted in inherent defects; often such as could not be completely removed by any amount of subsequent processing. These defects appeared as annular waves, bulges, inside laps, 35 distortions of the grain structure of the metal, and even tearing was frequently experienced.

In other instances, the sub-surface of the metal disclosed enlarged, or ruptured, grains and tiny 40 cracks. These enlarged grains, and cracks, spread when the work-piece was manipulated, and rendered it entirely unfit for service.

This severe upsetting action is due, largely, to the fact that all types of cross-rolling mills tend 45 to feed more metal into the inlet end of the pass than the rolls are capable of moving through the outlet thereof.

It is a well known fact that the profiles of the metal-working rolls which provide the convergent inlet end of the metal pass result in a component 50 opposed to the longitudinal movement of the work-piece. This component is neutralized by a component in the opposite direction, which is provided by the profiles of the rolls which define the divergent outlet end of the metal pass. When 55 the work-piece is in the inlet end solely this component of the rolls effectively retards its rate of longitudinal movement and, as the rotational motion remains unaffected, this retardation is advantageous in that it assists the centering of the 60 piercing plug.

The neutralizing component in the outlet end of the pass tends to accelerate the longitudinal movement of the work-piece after it leaves the inlet end of the pass. The rate of longitudinal movement of the work-piece in the outlet end of the pass is frequently so great as to cause it to be torn to such an extent that it can only be removed from the mill with considerable difficulty. 5

The combined effects of these resistances to the longitudinal movement of the work-piece results 10 in its leaving the pass with a velocity rarely greater than 55 per cent, and often less than 40 per cent of the velocity the metal-working rolls tend to impart.

Numerous tests of various cross-rolling mills 15 reveal that the cross-sectional area of the metal of the work-piece was first increased a small amount, then rapidly decreased, after which the rate of change was retarded to approximately zero. After this retardation to approximately 20 zero occurred, the area of the metal of the work-piece was again increased. These conditions are obviously not conducive to obtaining a work-piece possessing ideal characteristics but have, in the past, been regarded as a necessary evil. 25

If a plastic body is subjected to a strain, deformation begins at the place of greatest shear, and takes place in the direction of greatest shear. The initial deformation of the plastic body should be but slight, and increases subsequently at a rate 30 as rapid as its deformability will permit. In blooming mill practice, by way of example, the bloom is given several preliminary passes in which it is deformed but slightly, before it is rapidly reduced in area, or "hogged", as it is known in the 35 art.

This procedure prevents excessive stretching of the metal in any direction, and the elimination of enlarged or ruptured grains, and its accompanying 40 tiny cracks. In all existing types of seamless pipes and tube mills, the metal of the work-piece, moving in the manner described, is excessively upset and viciously distorted, or "hogged", with the resulting defects enumerated. Due to this unorderly movement of metal, it has been considered as being next to impossible to obtain an extremely thin-walled work-piece by piercing a solid billet. Therefore, a solid billet is always pierced to obtain a relatively thick-walled work-piece, and the wall of this work-piece subsequently reduced by numerous processing operations if its 50 temperature is maintained sufficiently high by the expedient of reheating. These numerous subsequent operations are costly and render some operations commercially impracticable. 55

In order to obviate the injurious characteristics and defects which are common to all present seamless processes, thin-walled tubing must be produced by maintaining an extremely orderly 60 movement of metal throughout the entire proc-

essing operation. I have discovered that such a movement can be obtained by coordinating the profiles of the component elements of the pass, such as the metal working rolls and a piercing 5 plug, in such manner that the axial advance of the metal is increased in a proper ratio. This ratio is, according to my discovery, such as will provide a "geometrical progression".

This is a well known geometrical law, and refers 10 to a progression in which each of a series of numbers, after the first, is obtained by multiplying the preceding by a constant multiplier which may be either greater or less than 1. As I have applied this law to the art of manufacturing seamless 15 pipes and tubes, it provides for the increasing of the several values of each elementary length increment of the metal of the work-piece in a "geometrical progression". That is to say, the width of each of the elementary length increments and 20 the several rates of longitudinal advance of a point in the work-piece, obtaining after successive roll contacts, form a "geometrical progression". This is also true of the reduction in the cross-sectional area of the metal of the increment when 25 the diameter of the pierced portions of the billet is maintained constant.

It is one of the objects of the present invention to provide a novel method and apparatus for manufacturing seamless pipes and tubes at a 30 greatly lowered cost of production, in addition to obtaining a vastly superior article.

Another object is the provision of a novel method and means for consistently obtaining a geometric widening of each of the successive increments of metal of the work-piece, or what might be termed a "natural flow" thereof, and in this manner reduce the wall thickness in an extremely orderly fashion such as is impossible to perform in using conventional types of seamless pipe and 40 tube mills. This "natural flow" results in a great reduction in internal laps and tears, less eccentricity in the work-piece, and the obtaining of leaving and trailing ends having their annular extremities lying in single planes at right angles 45 with respect to the axis thereof.

A further object is to provide a novel method and apparatus for effecting an accelerated delivery speed in seamless pipe and tube practices, which results in minimizing "distortion" or 50 "crowding" at intermediate points in the pass, in addition to extending the life-in-use of the component elements of the mill, such as the metal working rolls, piercing point and guides, and lowering the amount of power required.

A still further object is the provision of a novel method and apparatus for manufacturing seamless pipes and tubes in such manner as to enable the production of thinner walls, and the easy processing of alloy steels which have heretofore 60 been difficult, if not impossible, to work.

These and still further objects will be apparent after referring to the drawings, in which:

Figure 1 is a composite view of a piercing mill constructed in accordance with the teachings of 65 the present invention, and disclosing the relationship of one of the metal working rolls to one of the guide members which is shown, together with a portion of the work-piece in a plane substantially 90 degrees from its true position.

Figure 2 is a plan of the mill of Figure 1 and discloses the manner in which the increments of 70 the metal of the work-piece advance through the pass.

Figure 3 is a plan similar to Figure 2 showing in 75 section the relative positions and dimensions of

the increments obtaining after successive roll contacts.

Figure 4 is a plan similar to that of Figure 3, but disclosing a modified piercing plug and its effect on the increments. 5

Figure 5 is a diagram showing the method of ascertaining the taper of the piercing plug of Figure 4.

Figure 6 is a sectional elevation of the mill of the invention taken adjacent the outlet end thereof, and with the usual guide members removed for the purpose of simplicity. 10

Referring more particularly to the drawings, the numeral 2 designates a pair of metal working rolls which, when taken together, provide convergent portions 3 of substantial length, and divergent portions 4 of a similar length. The most constricted portions of the pass defined by the metal working rolls 2, which is known in the art as the "gorge", is indicated by the letter X. In 15 order to procure a forward feeding effect, the metal working rolls 2 are disposed with their axes of rotation oppositely inclined to each other with respect to a horizontal plane. This inclination is known as the "roll bearing angle", and is illustrated in the drawings as being 8 degrees. A tapered piercing plug 6 is disposed between the metal working rolls 2, providing a pointed extremity 7 and a rearward portion 8 which is substantially parallel to the divergent portions 4 thereof. 20 The piercing plug 6 is supported in position by a bar 9. A pair of upper and lower stationary guiding member 10 are intermediately disposed between the metal working rolls 2 and, when taken together, provide opposed contact faces 12 and 25 "centering" faces 13. These guiding members 10 limit the circumferential growth of the work-piece and divert metal displaced by the metal working rolls 2 into a longitudinal flow. 30

According to the teaching of the present invention, the contour of the tapered piercing plug 6 is 40 mathematically related to the adjacent surfaces of the metal working rolls 2 to provide that it will enter the work-piece 14 and permit successive increments of metal to be formed and reduced in 45 the natural manner mentioned by numerous contacts with the metal working rolls.

As is well known to those skilled in the manufacture of seamless pipes and tubes, the increments of metal are formed immediately after the 50 piercing plug, or other mandrel, enters the work-piece; one on either side of the pass. This principle may be likened to that of the twin-screw, and each of these increments advances helically and is followed by succeeding ones, thus filling 55 the pass.

The natural tendency of the metal displaced by the metal working rolls is to flow circumferentially and thus increase the diameter of the work-piece. The width of each increment, or helically 60 advancing strip, will increase very little without reaction against the guide members 10. The total width being rolled is, of course, made up of increments and spreading can, therefore, take place only at the ends and is always slight. 65

These successive increments are, by my invention, each advanced in a manner which is based upon the theory of "geometrical progression", as previously mentioned. Each term is derived by multiplying the preceding term by a constant 70 multiplier called the "ratio". This principle is applied directly to the width of each succeeding increment of work done by the metal working rolls in advancing the work-piece over the piercing plug. In this manner the metal of the work- 75

piece is made to "flow" in a very natural manner, and one such as will distribute the working thereof evenly throughout the metal-working portions of the pass. By adhering to this new teaching, 5 the volume of metal passing any point in the pass is constant. That is to say, as each successive increment is reduced in thickness it is increased in width in the proper proportion, as determined by the "ratio" or constant multiplier.

10 Obviously, the unalterable volume of metal moving past every point in the pass is cross-sectional area times speed. The total volume of metal flowing past all points in the pass being always the same, it follows that either a large area 15 is advancing slowly or a smaller one is advancing more rapidly. The lengths of the increments of metal vary according to the relationship of the metal working rolls with the piercing plug as it tapers toward the outlet end of the pass.

20 Once having found the common "ratio" of "geometrical progression", the widths of the various increments may be calculated and the piercing plug tapered in direct accordance therewith. It is, of course, considerably less difficult to change 25 the taper of the piercing plug than the contours of the metal working rolls. However, there are instances wherein a converse method is resorted to; as, for instance, when the processing operation is carried out over a cylindrical mandrel, or 30 bar.

The angles of the faces of the metal working rolls 2 are at 3°—30°, and their axes disposed at "bearing angles" of 8°, as previously mentioned.

35 One method of ascertaining the precise taper of a piercing plug such as will provide for a "geometrical progression" of the metal of the pierced portion of the billet is as follows:

The metal working rolls 2 are graphically illustrated in scale. The various diameters of billet 40 size and outside diameter and wall-thickness of the pierced work-piece are well known, and regulated according to practice. Let it be assumed that it is desired to pierce a billet 6 inches in diameter to a tubular work-piece having an outside 45 diameter of 6½ inches, and a wall-thickness of ½ of an inch. These dimensions are graphically represented and leave the dimensions of each successive increment of metal of the work-piece in the metal working portion of the pass to 50 be calculated in "geometrical progression". It is desirable to process as many increments as can conveniently be done in order to effect the greatest reduction possible in the thickness of the wall of the work-piece, and to divert this reduction 55 into elongation. The number of increments is therefore nominally selected; and is 8 in the present instance.

The initial reduction effected by the "necking down" function of the metal-working rolls 2, 60 while drawing the solid billet 14 into the "gorge" X, or most constricted portion of the pass, can easily be calculated, or fixed from a knowledge of past performance of the metal working rolls 65 illustrated, to be approximately 20 per cent. The area of a circle 6 inches in diameter is 28.3 square inches. Therefore, the area of the section of the billet 14 traveling through the "gorge" is .80×28.3, or 22.64 square inches. This figure is 70 designated as A_g (area at gorge), and its corresponding diameter D_g (diameter at gorge) is found by calculation to be 5½ inches.

The theoretical advance of the tubular work-piece 15 from the outlet end of the mill, as defined by the divergent portions 4 of the metal 75 working rolls 2, per half revolution is $.5 \pi D \cdot \tan$

8°. However, there is an additional advancing effect resulting from the contact of the pierced portion of the work-piece with the guiding members 10, and this has been found from experiment to increase the actual advance to approximately 5 1.10 times the theoretical. The actual advance of the pierced portion of the billet or tubular work-piece emerging from the outlet end of the mill can, therefore, be taken as $.5 \times 1.1 \times \pi \times D \cdot \tan 8^\circ$. This advance per half revolution is 10 therefore $.5 \times 1.1 \times 3.1416 \times 6.75 \times .1405$ (or 1.64 inches), as this means that the metal in the pass moved 1.64 inches before it left the piercing plug 6. This figure of 1.64 inches is taken to be the width of the last increment in the metal working 15 portion of the pass, and the widths of all preceding increments can be obtained by calculating the "geometrical progression". Accordingly, a common "ratio" of increment width is established and used in proper sequence as each dimension is calculated toward the pointed extremity 7 of the piercing plug 6. This "common ratio" may be determined by the use of the following formula:

$$r = \sqrt[n-1]{\frac{l}{a}} \quad 25$$

(wherein r equals common ratio; n equals number of increments of work; l equals advance per revolution at outlet end of pass; a equals advance 30 per revolution at inlet of pass).

The area of the cross-section of the tubular work-piece 15 leaving the outlet end of the pass is $\pi (D_o - t) t$, (or 7.5 square inches), and is called A_o (area at outlet). The area at the "gorge" X, 35 or most constricted portion of the pass, is 22.64 square inches, as previously mentioned, and all of it must go through the pass, although its speed at any intermediate point varies according to the distance therefrom. 40

The volume of metal passing any point in the pass is, however, constant, since it is the area of the cross-section times speed, and the rate of advance at the "gorge" can be calculated by simple inverse proportion; therefore, 45

$$7.5 : 22.64 = x : 1.64$$

(or $x = .543$). The advance of the increments at the outlet end of the pass is then 1.64 inches, and 50 that at the "gorge" is .543 inch.

The advance of each successive increment at intermediate points of the pass can be obtained by "geometrical progression", using the same formula 55

$$r = \sqrt[n-1]{\frac{l}{a}} \quad 55$$

This same result may be obtained if the various areas had been used: i. e.

$$r = \sqrt[n-1]{\frac{A_g}{A_o}} = \sqrt[n-1]{\frac{7/22.64}{7/7.5}} = \sqrt[n-1]{3.02} \quad 60$$

and $r = 1.170$.

Whichever method is used, it will at once become apparent that since the unchanging volume 65 moving past every point in the pass is equal to area times speed, it follows that in one instance the rate of increase in width of each successive increment as it advances is obtained, and in the other, the rate of decrease in the cross-section 70 moving through the pass. The total volume of metal flowing past all points in the pass is therefore always the same; it being either a large area advancing slowly or a smaller area advancing rapidly, as previously mentioned. 75

Having ascertained the common ratio (1.17) the widths of the successive increments may be calculated by first dividing $1.64 \div 1.17$, giving a result of 1.40, the width of the next preceding increment, and 1.40 divided by 1.17, giving the next, etc., thus working toward the "gorge". The widths of each of the eight successive increments are given in the following table, having been obtained by simple calculation:

Increment	a	b	c	d	e	f	g	h
Increment width.....	1.64	1.400	1.195	1.02	.872	.745	.636	.543

It is to be noted that in each instance the increment on the opposite side of the pass is designated by the character ' (or prime).

Having found the width of each successive increment, the depth thereof must be obtained in order to determine the taper of the piercing plug 6.

The unchanging volume flowing through the metal working portion of the pass is $\pi(d-t)tw$; wherein d is the mean outside diameter of each increment, t the thickness at its mid-portion, and w the width of the increment.

However, due to the fact that the actual advance of the metal through the pass is 1.1 times the theoretical, this formula can be utilized approximately as $\pi d t w$, as the missing values for any increment can be obtained if the other two are known.

The mean diameter of any increment is easily found, it being as much larger than the "gorge" diameter as the pass is widened by the divergent surfaces 4 of the faces of the rolls 2. This widening is twice the product of the distance of the mid-point out from the "gorge" and the tangent of the roll face angle. That is to say, increment a is of uniform thickness, being in what is known as the "parallel zone", and all of the other increments grow in thickness from this zone toward the "gorge" X. The average thickness is found from a volume constant which is fixed as follows:

$$\pi d t x w x = \text{volume}$$

at any point, and since π will always cancel out, this may be used as

$$d x t x w x .$$

Therefore, for the outlet, 6.211 times .375 times $1.64 = 3.83$.

From this figure the mean thickness of all increments may be obtained by dividing 3.83 by the product of mean diameter and the width of any increment. These products appear in the following table, in the last column of which the increment thicknesses are in reality the points of the plotted taper G of the piercing plug 6, as used to attain an approximate "geometrical progression":

Increment	Increment width	Increment mean diameter	Product width X mean diameter	Increment depth
a.....	1.64	6.211	10.20	0.375
b.....	1.400	6.027	8.45	.453
c.....	1.195	5.868	7.02	.532
d.....	1.02	5.732	5.84	.656
e.....	.872	5.618	4.90	.782
f.....	.745	5.520	4.12	.930
g.....	.636	5.439	3.46	1.105
h.....	.543	5.491	3.04	1.260
Total.....	8.051			

The mean depth of each increment is indicated by the prefix 1, as shown in Figure 3. The taper of the piercing plug 6 may be plotted along the inward extremities of the lines representing these depths, as shown by the full line G in Figure 3. If this is done, a "geometrical progression" will be had within close limits. This taper can be even more closely ascertained by calculating an infinite number of ordinates representing the depth of each increment at numerous points. However, this would entail a great amount of needless calculation for all practical purposes. Even if this troublesome method is pursued, the taper obtained would represent a plurality of constantly changing radii, and would be very difficult and expensive to produce in the pattern and machine shops.

Referring to Figure 4 of the drawings, the line R represents a modified taper for the piercing plug 6. This taper provides a working face which will more readily enter the solid billet 14 and will also reduce the thrust to which the bar 9 is subjected. In addition, it may be easily ascertained and produced in the pattern and machine shops with little difficulty. The method of determining this taper is illustrated in Figure 5, and is carried out in the following manner:

The working face of one of the metal working rolls 2 is graphically represented, as shown at 20. The radius of the largest diameter of the piercing plug 6 is also included, as shown at 60. A line 100 is used to graphically represent the center line of the pass. A line 200 is drawn at the roll face angle of $3^\circ 30'$ and made to intersect the line 100 on a line 300. A line 600 is used to define the usual rearward portion of the piercing plug 6 which is parallel to the divergent portions 4 of the metal working rolls 2. The line R represents a single radius of the taper desired for the piercing plug 6 which is closest to the plotted geometrical curve G of constantly changing radii. The radius of the pointed extremity 1 of the piercing plug 6 is taken from the intersection of the lines 100 and 200 and is indicated at r. The distance from the line 300 to the forward extremity of the parallel rearward portion of the piercing plug 6, which is indicated at 600, is called y, while the distance from the line 200 is designated x.

These values are as follows:

20=line at $3^\circ 30'$ to the center line 100 of the pass.

60=one-half of the diameter of the piercing plug 6 ($2(5.653) = 2.826$).

200=line in parallelism with line 20.

300=line $\frac{3}{8}$ inch in advance of gorge X.

600=line 2 inches long in parallelism with line 20.

R=radius of taper (unknown).

r=radius of pointed extremity 1 of piercing plug 6 ($\frac{3}{4}$ of an inch).

y=a distance of 6.575.

X=a distance of 2.31.

To determine R the following formula is used:

$$R = x + \frac{y^2(x-r)^2}{2(x-r)}$$

and the unknown proves, by calculation, to be approximately 15.3.

The modified taper R permits a substantial geometrical progression of the successive increments of metal over the piercing plug 6.

When using the plotted geometrically progressive taper G the piercing plug 6 provides an area of metal at the gorge X of the pass of approxi-

mately 22.64 square inches, while the area when using the modified taper R provides an area of 25.39 square inches at the same point. This difference amounts to a deviation of only 11.2%, which is rather insignificant so far as practical results are concerned. Obviously these differences in area between the tapers G and R progressively decrease toward the outlet end of the pass, with a corresponding decrease of percentage of deviation.

As a matter of fact, it will be readily apparent from Figures 3 and 4 that the last three increments of metal of the work-piece, on both sides of the pass (a-a', b-b', c-c') are processed in true geometric progression even if the modified taper R is used. The term "substantial geometrical progression" therefore contemplates a reasonable deviation from the theoretical curve, or preferred embodiment, such as within a limit of 18 per cent.

The term "tubular work-piece" as used in the claims is intended to define one which is hollow before it is completely worked, whether it is introduced to the rolls of the mill in the form of a solid billet or otherwise.

While I have shown and described several specific embodiments of my invention, it will be understood that I do not wish to be limited exactly thereto, since various modifications may be made without departing from the scope of my invention, as defined by the following claims.

I claim:

1. Apparatus for manufacturing seamless pipes and tubes comprising, in combination, a plurality of metal-working rolls and an intermediately disposed mandrel, the cooperating contact surfaces of said rolls and mandrel being constructed and arranged to provide a pass in which the several values of the elementary length increments of the metal of the work-piece are progressed geometrically.

2. Apparatus for manufacturing seamless pipes and tubes comprising, in combination, a plurality of metal-working rolls and an intermediately disposed mandrel, the cooperating contact surfaces of said rolls and mandrel being constructed and arranged to provide a pass in which the several values of the elementary length increments of the metal of the work-piece are progressed substantially geometrically.

3. Apparatus for manufacturing seamless pipes and tubes comprising, in combination, a plurality of metal-working rolls and an intermediate disposed mandrel, said mandrel having its contact surface constructed and arranged to provide between it and said metal-working rolls a pass through which the several values of each of the elementary length increments of the metal of the work-piece are progressed geometrically.

4. Apparatus for manufacturing seamless pipes and tubes comprising, in combination, a plurality of metal-working rolls and an intermediately disposed mandrel, said mandrel having its contact surface constructed and arranged to provide between it and said metal-working rolls a pass through which the several values of each of the elementary length increments of the metal of the work-piece are progressed substantially geometrically.

5. The method of manufacturing seamless pipes and tubes which includes the steps of helically advancing a tubular work-piece through a pass defined by a plurality of metal-working rolls wherein successive increments are formed by the successive roll contacts, and working the tubular

work-piece in such manner that the mean width of each of its elementary length increments so-formed are in geometrical progression.

6. The method of manufacturing seamless pipes and tubes which includes the steps of helically advancing a tubular work-piece through a pass defined by a plurality of metal-working rolls wherein successive increments are formed by the successive roll contacts, and working the tubular work-piece in such manner that the mean width of each of its elementary length increments so-formed are in substantial geometrical progression.

7. The method of manufacturing seamless pipes and tubes which includes the steps of helically advancing a tubular work-piece through a pass defined by a plurality of metal-working rolls wherein successive increments are formed by the successive roll contacts, and working the tubular work-piece in such manner that the mean thickness of each of its elementary length increments so-formed are in geometrical progression.

8. The method of manufacturing seamless pipes and tubes which includes the steps of helically advancing a tubular work-piece through a pass defined by a plurality of metal-working rolls wherein successive increments are formed by the successive roll contacts, and working the tubular work-piece in such manner that the mean thickness of each of its elementary length increments so-formed are in substantial geometrical progression.

9. The method of manufacturing seamless pipes and tubes which consists in the steps of helically advancing a tubular work-piece through a pass defined by a plurality of metal-working rolls, wherein successive increments are formed by the successive roll contacts, and changing the several dimensional characteristics of each of the elementary length increments of the tubular work-piece in geometrical progression.

10. The method of manufacturing seamless pipes and tubes which consists in the steps of helically advancing a tubular work-piece through a pass defined by a plurality of metal-working rolls, wherein successive increments are formed by the successive roll contacts, and changing the several dimensional characteristics of each of the elementary length increments of the tubular work-piece in substantial geometrical progression.

11. The method of manufacturing seamless pipes and tubes which includes the steps of helically advancing a tubular work-piece through a pass defined by a plurality of metal-working rolls wherein successive increments are formed by the successive roll contacts, and working the tubular work-piece in such manner that the mean cross-sectional area of each of its elementary length increments so-formed are in geometrical progression.

12. The method of manufacturing seamless pipes and tubes which includes the steps of helically advancing a tubular work-piece through a pass defined by a plurality of metal-working rolls wherein successive increments are formed by the successive roll contacts, and working the tubular work-piece in such manner that the mean cross-sectional area of each of its elementary length increments so-formed are in substantial geometrical progression.

13. The method of manufacturing seamless pipes and tubes which includes the steps of helically advancing a solid work-piece into a pass defined by a plurality of metal-working rolls,

5 piercing the solid work-piece, whereby successive increments are formed by the successive roll contacts, the piercing step effecting not more than 30 per cent of the total reduction in cross-sectional area of the work-piece before it reaches the most constricted portion of the pass, and working the pierced work-piece in such manner that the several dimensional values of each of its elementary length increments so-formed are in 10 geometrical progression.

14. The method of manufacturing seamless pipes and tubes which includes the steps of helically advancing a solid work-piece into a pass defined by a plurality of metal-working rolls, 15 piercing the solid work-piece, whereby successive increments are formed by the successive roll contacts, the piercing step effecting not more than 30 per cent of the total reduction in cross-

sectional area of the work-piece before it reaches the most constricted portion of the pass, and working the pierced work-piece in such manner that the several dimensional values of each of its elementary length increments so-formed are in substantial geometrical progression. 5

15. The method of manufacturing seamless pipes and tubes which includes the steps of helically advancing a tubular work-piece through a pass defined by a plurality of metal-working rolls wherein successive increments are formed by the successive roll contacts, and working the tubular work-piece in such manner that the dimensional characteristics of each of the elementary length increments so-formed are within 10 an 18 per cent deviation of those values which constitute geometrical progression. 15
